UNITED STATES PATENT OFFICE.

LOUIS F. DESPRES, OF LEBANON, NEW HAMPSHIRE.

LAMP WRENCH.

Application filed June 21, 1922. Serial No. 569,772.

To all whom it may concern:

Be it known that I, LOUIS F. DESPRES, a citizen of the United States, residing at Lebanon, in the county of Grafton and State 5 of New Hampshire, have invented certain new and useful Improvements in Lamp Wrenches, of which the following is a specification, reference being had to the accompanying drawings.

10 This invention relates to wrenches and more particularly to wrenches for use on cylindrical objects, such as lamps.

An object of the invention is to provide a wrench of this character capable of being 15 quickly adjusted to suit the diameter of the object on which it is used.

Another object of the invention is to provide a wrench of this character adapted to surround the object to be tightened, one 20 portion of the wrench being provided with bearing means and the opposite portion arranged to engage said bearing means, said bearing means being adjustable according to the movement of the last mentioned portion 25 of the wrench.

It is a further object of the invention to provide a wrench of this character including a length of material arranged to surround the object, one end of the length being provided 30 with a movable bearing member, said bearing member having anti-friction means arranged to be engaged by the opposite end of the length to substantially permit all portions of the length to frictionally engage 35 the object.

With these and other objects in view, the invention consists in the improved construction and arrangement of parts to be herein-after more particularly described, fully 40 claimed and illustrated in the accompanying drawings, in which:—

Figure 1 is a plan view of a lamp showing the invention applied;

Figure 2 is a fragmentary elevation of the 45 wrench structure shown in Figure 1;

Figure 3 is a plan view of the wrench showing the handle disconnected; and

Figure 4 is a longitudinal sectional view 50 showing the mounting of the rollers and pivotal connection of the adjusting member.

Referring to the drawings, 5 designates a strip of resilient material relatively wide to permit said strip to firmly engage an object. The length of the strip may be made to correspond 55 to the object on which the wrench is to be used. The size of the wrench, how-

ever, does not interfere with the adjusting means thereof.

The end portion 6 of the strip is substantially coiled to provide a hinge knuckle 7 which extends laterally of the strip. A bearing and adjusting member 8 is provided, said member consisting of a frame including side rails 9 and end rails 10. The end rails 10 are secured at their extremities to the extremities of the side rails, while each of the side rails is substantially bent at its central portion so as to dispose the end portions of said side rails in divergent relation to each other and in this way dispose one end portion of the frame substantially in angular relation to the opposite end portion. Before the end rails 10 are engaged with the side rails, a roller 11 is mounted on each end rail, longitudinal movement of the roller relative to the end rail being prevented by contact of said roller with the end portion of the side rails. The rollers 11 are intended to correspond in length to the distance between the side rails, the width of the frame 80 being slightly greater than the width of the strip 5.

In order to connect the adjusting and bearing frame to the end portion 6 of the strip, the central portion of each of the side 85 rails is provided with an opening 12 adapted to receive the reduced ends of a pintle 13, said pintle extending through the hinge knuckles 7 of the end portion 6 of the strip and by means of which the frame 8 is pivotally connected to the strip for oscillating movement. It will be noted by this arrangement that while each of the rollers 11 is substantially disposed in alignment with each other they are disposed to one side of 90 the pivotal connection of the frame to the wrench or strip. The purpose of this is to prevent contact of the end portions of the strip with each other in the operation of the wrench. The opposite end portion 13 of the strip is provided with a handle 14, said handle being secured centrally of the extremity of said end portion. To assure a positive gripping action of the wrench on the work, the inner face of the strip 6 is 95 provided with a layer of anti-slipping material 15, such as rubber, etc.

In the use of the wrench, the strip or body member of the wrench is engaged with the object to be tightened or loosened 110 and the handle 14 passed under one roller 11 above the pintle 13 and beneath the other

roller 11, the outer surface of the end portion 13 of the body member or strip being arranged to engage the rollers. When the handle is pulled by the operator it causes the rollers to firmly engage the end portion 13 of the strip and urge the entire strip into binding engagement with the object or work. When the wrench is under strain, one end portion of the frame is disposed substantially at right angles to the body member 5, while the opposite end portion of the frame is disposed substantially in alignment with the end portion 6. This permits the end portion 13 of the strip to extend outwardly away from the end portion 6 and at the same time permits one roller to hold the end portion 13 of the wrench in engagement with the object or work, while the opposite roller assists in reducing the friction between the frame 8 and the end portion 13. In view of the above advantages, the wrench may be efficiently used by anyone, as a great amount of strength is not necessary.

From the foregoing it will be readily seen that this invention provides a novel form of wrench adapted for use on any cylindrical object and wherein the entire body portion of the wrench is caused to engage the object at all points longitudinally of the body member, with the exception of the extremity of the end portion 13 which must necessarily pass through the bearing and adjusting frame. Furthermore, by the use of the movable bearing and adjusting frame the adjustment may be made with rapidity and accuracy and the wrench may be operated by a person with little strength. All of these features are possessed by a device which is compact and simple in construction.

What is claimed is:—

1. A wrench of the character described comprising a resilient strip, a frame pivoted

at its middle to one end of the strip, rollers carried by opposite ends of the frame, the end of the strip remote from its point of connection to the frame being provided with a handle, said last named end portion of the strip being adapted to extend through the frame and engage the rollers in spaced relation to the pivotal connection of the frame to the strip.

2. A wrench of the character described comprising a resilient strip having a hinge knuckle formed on one end thereof, a bearing and adjusting frame including side and end members, the side members of the frame being bent at their central portions so as to dispose the end portions of said side members in divergent relation to each other, a bar extending between the central portions of the side members, said bar being disposed in the hinge knuckle of the strip, rollers carried by the end members of the frame substantially in alignment with each other, one of said rollers urging the opposite roller into engagement with the strip upon engagement of the opposite end of the strip with said rollers.

3. A wrench of the character described comprising a strip having a knuckle formed on one end, a rectangular frame having a cross bar at its middle, the cross bar being pivoted to one end of the strip, a portion of the frame on one side of the cross bar being angular with relation to the portion of the frame on the other side of the cross bar, the ends of the frame carrying rollers, that end of the strip opposite the end to which the frame is attached being formed with a handle whereby said strip may be threaded beneath one of the rollers over the hinge beneath the other roller.

In testimony whereof I hereunto affix my signature.

LOUIS F. DESPRES.
